UNITED STATES PATENT OFFICE.

SAMUEL DIESCHER, OF PITTSBURG, PENNSYLVANIA, ASSIGNOR TO SAMUEL DIESCHER & SONS, OF PITTSBURG, PENNSYLVANIA, A COPARTNERSHIP OF PENNSYLVANIA.

HEATING-FURNACE.

SPECIFICATION forming part of Letters Patent No. 693,120, dated February 11, 1902.

Application filed May 20, 1901. Serial No. 61,034. (No model.)

To all whom it may concern:

Be it known that I, SAMUEL DIESCHER, a citizen of the United States, residing at Pittsburgh, in the county of Allegheny and State 5 of Pennsylvania, have invented or discovered certain new and useful Improvements in Heating-Furnaces, of which improvements the following is a specification.

The invention described herein relates to 10 certain improvements in furnaces for the progressive heating of long lengths of metal rods, strips, &c.

In an application, Serial No. 61,033, filed May 19, 1901, I have described and claimed 15 a furnace consisting of a heating-chamber and a series of combustion-chambers arranged at intervals along the furnace and below the bottom or floor of the heating-chamber. The invention set forth herein consists in certain 20 further or additional improvements in the type of furnace forming the subject-matter of said application.

In the accompanying drawings, forming a part of this specification, Figures 1 and 2 are 25 longitudinal sections on planes indicated, respectively, by the lines I I and II II, Fig. 3. Figs. 3 and 4 are transverse sections on planes indicated, respectively, by the lines III III and IV IV, Fig. 1. Fig. 5 is a horizontal section 30 on a plane indicated by the line V V, Fig. 3. Fig. 6 shows a plan and sectional elevation of the combustion-box, and Fig. 7 is an end elevation of the same.

The furnace is formed with the long continuous heating-chamber 1, having its ends closed by movable doors 2 and 3. Above the heating-chamber is formed a flue or passage 4, open at one end and connected by a series of ports 5 with side flues 6 and 7. These side 35 flues are connected by ports 8 and 9 with the fire boxes or chambers 10, which are preferably formed of metal and embedded in the bottom of the furnace, with their upper surfaces flush, or nearly so, with the bottom of 40 the heating-chamber. The ports 8 and 9 are formed in the ends of these fire boxes or chambers and are adapted to be closed by slide-valves 11, moving in suitable guides formed in the top of the fire-boxes. Within these 45 fire-boxes are placed burners 12, having their

outer ends connected with suitable gas-supply pipe 13 and having valves 14 arranged between the supply-pipe and the burners. Through the upper walls of the fire-boxes are formed slots 15, through which the heat and 55 products of combustion can pass up into the heating-chamber, from which they escape through the outlet-flue 16, located at the front or charging end of the furnace.

In using this furnace the rods or strips of 60 metal are passed into the charging end and thence move continuously through the furnace, being subjected during their traverse of the furnace to gradually-increasing heat. By the proper regulation of the air and gas 65 valves the heat to which the rods are subjected at any point in their traverse can be increased or decreased, as required, by the size of the rods or strips and their rate of movement through the furnace. The air used enters 70 the flue 4 above the heating-chamber and passes down through the side flues 6 and 7, so that it will become highly heated by contact with the highly-heated inner walls of said flues and will in turn heat the gas as it commingles therewith, so that the furnace operates to a large extent upon the regenerative principle. As the combustion occurs within the fire-boxes only the heat and products of 75 combustion will come into contact with the rods or strips, so that the latter will not be subjected to any severe cutting action or oxidation. The number and location of the fire-boxes will be dependent upon the length of the heating-chamber and the size of articles to be heated and the desired speed of 80 movement of the articles through the furnace. 85

I claim herein as my invention—

1. A furnace having in combination a heating-chamber having oppositely-arranged charging and discharging openings, a series of fire boxes or chambers arranged below the floor of the heating-chamber and provided with openings at an angle to a straight line 90 passing through the charging and discharging openings for the passage of heat and products of combustion into the heating-chamber, and burners arranged in the fire boxes or chambers, substantially as set forth. 95 100

2. A furnace having in combination a heating-chamber having charging and discharging openings at its ends, air-flues extending along the top and sides of the heating-chamber, a
5 series of two or more slotted fire boxes or chambers arranged transversely of the heating-chamber and below the floor thereof, valved ports connecting the ends of the fire-boxes with the air-flues, and burners ar-

ranged in the fire-boxes, substantially as set forth.

In testimony whereof I have hereunto set my hand.

SAMUEL DIESCHER.
